SEMI-AUTOMATIC PISTOL

William B. Ruger, Southport, Conn., assignor to Sturm, Ruger & Company, Inc., Southport, Conn., a corporation of Connecticut

Application March 20, 1958, Serial No. 722,669

7 Claims. (Cl. 89—194)

This invention relates to semi-automatic pistols of the blow-back type, and has for its object the provision of certain improvements in such pistols. The invention provides an improved receiver and breechblock mechanism in combination.

The receiver of the invention is preferably a unitary structure having adjacent longitudinal holes, such as cylindrical bore holes, one for the operation therein of a reciprocating breechblock, and the other for a return spring and rod means for operatively connecting the return spring to the breechblock. A reciprocal striker having a contained spring and integral firing pin is mounted in the breechblock. One important feature of the invention is the provision of a cross-pin, removably inserted into a transverse hole in the receiver that performs at least three important functions: (1) as a guide and stop for the breechblock, (2) as a base against which the striker spring is compressed, and (3) as a stop for the return spring.

The breechblock is generally cylindrical and has a flattened upper surface at the rear which slides under the cross-pin and is prevented from turning. The forward edge of the flattened portion is a shoulder which strikes the cross-pin to arrest the rearward movement of the breechblock. The striker has a longitudinal bore at the rear for receiving its spring and follower rod which has an enlarged rearward base having a transverse slot. The striker, together with its operating spring and follower rod, are mounted in a longitudinal hole in the breechblock and the cross-pin is inserted in the slot in the base to secure the follower rod in position. The breechblock has a knob projecting at the rear for hand operation and the rod for the return spring is attached to this knob. The return spring bears at one end on a collar surrounding the rod, and at the other end, on a head on the rod. The cross-pin has a notch which engages a shoulder in the collar for holding the collar in position and providing a locking means for holding the cross-pin in position. The cross-pin can be removed simply by turning it one-quarter turn and pushing it out of its hole thereby freeing the breechblock, striker, return rod and return spring, for their individual removal. The cross-pin provides a safety feature since the gun cannot be fired unless the cross-pin is in its locked position.

Another important feature of the invention is the combination of a striker and an indicator for showing when the striker is cocked which are mounted in the breechblock. The striker has an integral and depending lug projecting through an opening in the breechblock which has a surface for engaging the sear and a shoulder for operating the indicator.

In its more complete aspects the pistol comprises a removable grip member, a magazine, a trigger, sear and trigger disconnector which will be discussed only generally to the extent necessary to describe the functions of the aforementioned elements.

These and other novel features of the invention will be better understood after considering the following discussion with reference to the accompanying drawings, in which:

Fig. 1 is a fragmentary view of a semi-automatic pistol of the invention with parts shown in vertical section;

Fig. 2 is a plan view of Fig. 1 with parts shown in section;

2

Fig. 3 is a sectional view at 3—3 of Fig. 1, and Fig. 4 is a fragmentary view at 4—4 of Fig. 2.

The automatic pistol illustrated in the drawings comprises a barrel 1 screwed into the receiver 2 which has an integral trigger guard 3. The rear part of the receiver has an upright recess into which is inserted the heel plug 4. A plastic grip member 5 is held in position on the receiver and heel plug by the screw 6 which extends to the butt end of the grip member (not shown). The magazine 7 is inserted into the grip member and is held in position by the release-catch 8. As shown, the magazine is in a partly withdrawn position. As best shown in Figs. 2 and 3, the receiver has two adjacent cylindrical holes, preferably bores, 10 and 11, the bore 10 being in an extension at the left side of the receiver. The breechblock 12, generally cylindrical and reciprocal in the hole 11, has a knob 13 on the exterior for operating the breechblock manually.

The front of the breechblock has an extractor 14 of common construction. The rear upper portion is cut off to form the flat surface 15 and the shoulder 16. The bore hole 17 in the breechblock extends from the rear to the line 18 where it joins a milled slot 19 which opens into the cartridge chamber for the head of a rim-fired cartridge. The striker 22 has a cylindrical hollow part 23 and a flat projecting part 24 the end of which functions as the firing pin. Within the hollow striker 22 the striker spring 25 is inserted. The guide rod 26 for the spring has a head 27 forming a base for the spring. The head has a transverse half-round cut 28 the function of which will appear later. The striker has a depending lug 29 the forward face of which is a polished face for the sear to catch.

The knob 13 of the breechblock is bored and threaded to receive the rod 32 which is reciprocal in the cylindrical bore hole 10 by movement of the breechblock. One end of the rod has a head 33 which provides a stop for the return spring 34 the other end of which bears against the collar 35. This collar has a right angle and also an arcuate cut which leaves the upright shoulder 36 the function of which will appear later. The rod is flattened at 37 to permit it to slide under the cross-pin, thus providing for the use of a relatively large rod, and preventing it from turning.

The breechblock also has the longitudinal bore hole 37 which is partly threaded to receive the hollow screw 38. Within the hole 37, the indicator pin 40 and its spring 41 are mounted, and the end 42 of the pin extends through the screw 38. The head of the pin is engaged by the lug 29 of the striker when the striker is cocked as shown in Fig. 1 to push the end 42 beyond the knob 13 to indicate that the gun is cocked. When the striker is released, the spring 41 moves the pin inward to indicate that the gun is not cocked.

The receiver has a transverse bore hole 50 into which the cylindrical cross-pin 51 is mounted. This pin is pushed into position and turned by a coin or the like in the slot 52 to position the right-angle notch 53 of the cross-pin in engagement with the edge 36 of collar 35. This secures the cross-pin in position from which it may be removed by reversing the operation. The cross-pin serves three important functions:

First, the flat surface 15 slides under the cross-pin and holds the breechblock in its proper position, and the shoulder 16 forms a stop to arrest the rearward travel of the breechblock.

Second, the cross-pin is inserted across and in the curved slot 28 of the head 27 thereby providing a secure base for the striker spring 25.

Third, the cross-pin secures the collar 35 and provides a secure base for the return spring 34 thereby also locking the cross-pin in position.

By simply turning the cross-pin clockwise as shown in Fig. 4, the collar is moved to the left against the spring 34 thereby removing the notch of the cross-pin from engagement with the collar, and the cross-pin may be pushed out of its hole 50. The breechblock and its attached rod 32, striker, return spring, and related elements can then be removed from the receiver.

The heel plug 4 has a transverse open-slot 55 which is hooked over the pin 56 in the receiver. The heel plug 4 is then swung to the position shown in Fig. 1 and the pin 57 is inserted through a hole in the receiver and heel plug to secure the heel plug in position. As shown in broken lines, the heel plug projects up into the hole 11 and has a terminal snout 58 that is the ejector for throwing the cartridge cases through the port 59. The breechblock is cut out underneath to clear this snout as it moves back and forth.

Since the pistol is a semi-automatic, the trigger, trigger release or disconnector, sear and safety will be described only generally as they are not claimed in this application. The trigger 65 is pivotally mounted in the receiver on pin 66 which is held in position by the spring catch 67. The trigger has a bore hole in which the spring 68 and plunger 69 are inserted. The plunger bears on a flat surface of the receiver and the spring opposes the trigger pull. The trigger rod 70 is a flat bar mounted in a slot in the receiver and is pivotally connected to the trigger by the pin 71. It is also pivotally connected to the receiver by the pin 72 in the elongated hole 73. The right end 74 of the trigger rod is bent inwardly as shown in Fig. 1. The sear 75 is a flat plate mounted in a slot in the heel plug 4 and is pivotally connected thereto by the pin 57. As shown in Fig. 1, the sear is in engagement with the catch surface on lug 29 of the striker. The right lower edge of the sear is in engagement with a plunger 76 mounted in the heel plug 4 with a spring 77 which urges the sear in a counter-clockwise position. The flat curved disconnector plate 78 is pivotally connected to the receiver on the pin 79. (This pin may include safety means for preventing accidental firing.) The lower portion of plate 78 has a coupler bar 80 pivoted thereto on pin 81. The coupler bar has a rounded end 82 (inwardly as viewed in Fig. 1) which operates in the slot 83 of the sear plate 75 and a square-cut end 84 which is engaged by the bent end 74 of the trigger rod 70. The plate 78 and the coupler bar 80 are constantly urged in a clockwise turning action by the plunger 87 and spring 88 which are mounted in a hole in the heel plug 4.

When the trigger is pulled from the position of Fig. 1 the spring 68 is compressed, the rod 70 pivots on pin 72 and the end 74 moves downward on the square end 84 of the coupler bar 80 thereby causing the rounded end 82 to push the sear 75 clockwise against the plunger 76 and spring 77. This moves the sear out of engagement with the striker lug 29 and the striker is released to ignite the cartridge. When the breechblock moves rearward following the explosion, the curved upper end of the disconnector plate 78 is engaged by the curved shoulder 85 on the breechblock and is depressed in which place it remains until the breechblock returns to the closed position of Fig. 1. When the breechblock is rearward and the disconnector plate 78 is depressed at its upper end, the coupler bar 80 is drawn to the right or rearward and the end 84 is removed from the possibility of engagement with the end 74 of the trigger rod. Accordingly, if the shooter hangs onto the trigger after shooting, the action of the breechblock effects a disconnection of the trigger from the sear, enabling the sear to engage the notch 29 and hold the striker cocked. When the breechblock is returned to its firing position, the relief area under the curved opening 86 is over the disconnector plate and the curved upper end may rise to the position shown in Fig. 1 due to the pressure exerted by plunger 87 and spring 88. When the trigger is re-

leased, the breechblock being closed, the end 74 of the trigger rod moves up to the position shown in Fig. 1 and the plunger 87 and spring 88 push the coupler bar forward to the position shown in Fig. 1, in which position firing may be resumed.

I claim:

1. A semi-automatic blow-back pistol which comprises a receiver, adjacent longitudinal holes in the receiver, a breechblock reciprocally mounted in one hole, a breechblock return spring mounted in the other hole, means operatively connecting the return spring to the breechblock, a striker and spring therefor in the breechblock, a removable cross-pin in the rearward portion of the receiver, means providing a stop for the striker spring which bears against the cross-pin, means on the breechblock to engage the cross-pin on the rearward travel of the breechblock, and means engaging the cross-pin forming a base for the return spring.

2. A semi-automatic pistol according to claim 1 which comprises a follower rod for the return spring attached at one end to the breechblock and having a head at the opposite end against which the spring bears.

3. A semi-automatic pistol according to claim 2 which comprises a collar around the follower rod having a shoulder into which a notch of the cross-pin makes locking engagement.

4. A semi-automatic pistol according to claim 1 which comprises a striker having a longitudinal hole in which the striker spring is mounted, a firing pin at one end of the striker, a lug depending from the striker having a surface for engaging a sear and a spring-pressed indicator adapted to project rearward of the breechblock when engaged by the lug in the cocked position to indicate that the striker is cocked.

5. A semi-automatic blow-back pistol which comprises a receiver, adjacent longitudinal holes in the receiver, a breechblock reciprocally mounted in one hole, a breechblock return spring mounted in the other hole, means operatively connecting the return spring to the breechblock, a striker in the breechblock, a transverse hole in the receiver which cuts across the holes for the breechblock and the return spring, the breechblock having a cut out flattened portion and a shoulder, said striker having a spring and follower rod mounted therein, a head on the follower rod having a transverse groove, a cross-pin inserted in the transverse hole over the flattened portion of the breechblock and against which the shoulder makes contact when the breechblock travels rearward, the cross-pin being inserted in the groove of the follower head to secure the follower head and provide a base for the striker spring, and locking means on the cross-pin to secure it in position, said cross-pin being removable from its locking engagement when turned.

6. A semi-automatic pistol according to claim 5 which comprises a knob on the rearward end of the breechblock for manual operation, a spring pressed indicator pin projectable from the knob, and means on the striker for engaging the indicator when the striker is cocked to push it to an indicating position.

7. A semi-automatic pistol according to claim 5 which comprises a follower rod for the return spring operatively connecting the return spring to the breechblock, and means on the follower rod for the return spring to engage the cross-pin to hold it in its locked position.
